[57] CLAIM

The ornamental design for card and chip rack, as shown.

DESCRIPTION

FIG. 1 is a top perspective view showing the front, top, and one side of a card and chip rack showing my new design; and

FIG. 2 is a perspective view illustrating the back, bottom, and opposite side of the rack; and

FIG. 3 is a side elevation view of the device.

Fig. 1.

Fig. 2.

Fig. 3.
